OIL SWITCH

Application filed February 6, 1932. Serial No. 591,302.

This invention relates to oil switches and is particularly concerned with novel and improved features in oil and air break disconnect switches. Such switches are used for establishing and for maintaining connections between different cables, such as between main lines and feeders, or between overhead and underground lines, or combinations thereof, and for disconnecting the established connections when desired or necessary for the operation of the system.

Trouble and danger of various kind might occur during the maintenance of such connections, as well as during the connecting and disconnecting operations of switches of this character. The principal aim of this invention resides in the provision of novel features and improvements of such a nature as to furnish a commercially simple and technically satisfactory device, and thereby eliminating trouble and danger to the service and to the maintenance force. The various objects accomplished by the invention are briefly enumerated below:

23 One object resides in the provision of a simplified device containing standardized parts and elements whereby it is made possible to connect overhead lines or underground cables interchangeably to either side of the housing or container thereof.

Another object relates to improved switch mechanisms disposed in the interior of the housing or container and operable from the outside, whereby established connections can be successively interrupted at a plurality of points, namely, at a point disposed within the liquid insulating medium, such as oil, and at a point disposed within an air space.

A further object is realized by the provision of means within the housing or container and cooperating with the switch mechanism, whereby the transmission of tension or voltage variations occurring along the surface of the liquid insulating medium, to the lines, is entirely avoided.

Still another object resides in improved contact mechanisms furnishing a positive and reliable operation with a minimum amount of wear.

50 Other objects and features will appear as

the detailed description progresses which is rendered below with reference to the accompanying drawings.

In these drawings:

Fig. 1 represents a sectional side elevation through a device embodying the novel and improved features intimated above. The section is taken through the housing approximately on lines 1—1 indicated in Fig. 2, and shows certain parts in cross section and others in elevation;

Fig. 2 is a sectional side elevation taken through the housing approximately on lines 2—2 in Fig. 1, also showing parts in cross section and in elevation, respectively, and

55 Figs. 3 to 7, inclusive, illustrate improved contact mechanisms.

Like reference numerals applied in the Figs. 1 and 2 indicate like elements and parts. Unessential details have been omitted for the sake of a clear and comprehensive description.

70 The device comprises essentially a container or housing 10, preferably made of metal, and provided with flanges 11 which may be welded thereto. A top portion 12 is secured to the housing 10 by means of flanges 13 which register with the flanges 11 as shown. Gaskets may be interposed between the flanges if desired. The attachment may be accomplished by means of removable bolts such as 14. It will be observed that the flanges 13 of the top portion, secured to the sides thereto, project laterally into the container as is particularly apparent from Fig. 2, the projecting portions being indicated by the numeral 15. Secured to these projecting flange portions inside the container are certain mechanisms which will presently be described in detail.

75 The top portion 12 is provided with two oppositely disposed openings or apertures of the same size and shape as indicated in Fig. 1 at 16 and 17. The device is adapted to establish a plurality of connections, between cables or lines and the like, entering from one side and leaving the device on the other side, and the above mentioned openings are conveniently situated so as to permit the entry and exit of the respective connections. A cover box 18 is mounted on the

55

60

65

70

75

80

85

90

95

100

right side of the device shown in Fig. 1, covering the opening 17. This cover box 18 is secured to the top portion 12 of the container by means of bolts such as 19 and 20, 5 and attached thereto, by means of bolts 21 and 22, is the connecting sleeve 23. It is understood that gaskets may be employed wherever it is desired or necessary. A cable such as the cable 24 enters into the device 10 through the sleeve 23. Other cables entering at this side of the device are connected through similar connecting sleeves mounted on the cover box 18. Secured to the other side of the top portion 12 and covering the 15 opening 16 therein, is a side cover 25, being attached by means of removable bolts such as 26 and 27. Insulators such as 28 and 29 carrying certain terminals are mounted laterally in cooperation with the cover 25, as 20 shown.

The connections between the corresponding cables and lines are established by means of switch mechanisms disposed within the container and operable from the outside. 25 The structure and operation of these mechanisms will be presently explained. However, attention may be called at this point to the simplicity of construction of the entrance and exit of the various lines and cables. 30 The openings in the top portion 12 of the housing or container are of substantially identical dimensions and shapes. The covers 18 and 25 are interchangeable, and either of the covers can, therefore, be secured to 35 either side of the top portion 12. The various parts and elements of the switch mechanism may be standardized and may be used on either side of the container or housing. Hence, my invention provides a 40 simple device, comprising standardized, interchangeable parts, which may be readily attached or removed and exchanged, depending upon the particular location and the character of the cables and lines entering and leaving the device, respectively. 45

The housing or container is provided with insulating walls such as indicated at 90 to 50 93, inclusive, cooperating with an insulating base 94. A lid 30 is suitably secured to the top portion 12 covering the opening 31 thereon. The attachment of this lid may be accomplished by means of suitable bolts or the like. 55

The manner in which certain connectors, 55 switch terminals, and the corresponding cable and line connections are provided within the container will be described next, particularly with reference to Figures 1 and 2. It may be mentioned at this point that the 60 device is designed for a plurality of connections, accommodating, in the example illustrated, three sets of connections each being connected through certain switching equipment.

65 Secured to the flange portions 15 project-

ing laterally into the container are the members 32 and 33. Only portions of the flange member 15 and the mounting member 33 are shown in Figure 1 in order to keep the drawings clear and simple. The members 32 and 33 hold a mounting plate 34 extending transversely across the container inside thereof as is apparent from Fig. 2. Sleeves such as 35, 36 and 37, one for each connection are carried by the plate 34. The sleeve 36 is shown slightly shorter in Figure 1 than in Figure 2 in order to illustrate other parts more clearly. The insulators 38, 39 and 40, one for each connection, extend through the sleeves 35, 36 and 37, respectively, and are firmly secured thereto by cementing as is indicated in Fig. 1 by the reference numeral 41 showing how the insulator 39 extends through the sleeve 36 and how it is cemented thereto. A connector extends through each insulator, projecting from the top thereof, in the form of a threaded lug such as indicated at 42, 43 and 44, respectively. The terminals 45, 46 and 47 of the cables are fastened to the corresponding connector lugs by means of nuts such as 48, 49 and 50, respectively, as shown. Nuts such as 51, 52 and 53, hold the connectors in assembly with the corresponding insulators. Secured to the other end of each of the insulators, in contact with the corresponding connector therein, is a yieldable spring leaf contact, such as shown at 54, 55 and 56, the mounting thereof in conductive relation with the connector being accomplished by means of a suitable bolt or nut such as indicated at 57, 58 and 59. It will be seen that these yieldable contacts are reinforced by leaf springs in order to 100 secure the required mechanical strength and flexibility and thereby securing reliable operation.

The foregoing description shows that each of the various cables, such as the cable 24, enters through a wiping sleeve such as 23 on one side of the device (the sleeves being mounted on the cover box such as shown at 18) and that each cable is attached to a connector extending through an insulator such as 39 and terminating in the yieldable contact such as 55. 110

The above completes the description of the manner in which the entry of the various cables into the device is effected. It is understood, of course, that I employ the terms—"entry" or "exit"—or equivalent language, only for the sake of description and not for the purpose of limitation. The entry or exit of cables or lines will be determined by the use of the device, and, since 115 my invention provides for utmost standardization and interchangeability, it is apparent that this interchangeability will also affect the terminology to be employed. What might be properly termed the—"entry"—of 120

70

the cable or line in one case, may be referred to as—"exit"—in another case.

The description will be now continued with particular reference to Fig. 1. This figure shows only the operating mechanisms and various other parts belonging to one set of connections. It will be recalled, however, that the device contains three such connections as is indicated in Fig. 2. Insulating partitions may be provided between the sets of connections if desired. The manner in which a cable enters into the device, and in which it is secured to a connector terminating in a yieldable or flexible contact, has been explained. The provisions for the exit of the cables or lines will be described next.

Secured to the cover 25 shown on the left side of the device in Fig. 1, are insulators such as 28 and 29, one being disposed within the device and the other projecting therefrom. A connector extends through these insulators and terminates within the device in a terminal lug projecting from the insulator 28 as shown at 61. Attached to this terminal lug by means of bolts such as 62 and 63, and depending therefrom, is a connector link 64. The switch contact 65 projects into this link and is slidable therein, as will be presently described. The lines or cables such as 60 extend from the device as shown, and each is connected to a corresponding feeder or line cable provided in the system.

The switch mechanism set for establishing the connection between a cable such as 24 and a line or cable such as 60 comprises elements or parts which are best illustrated in Fig. 1. It should be borne in mind in reading the following description, that the mechanism accomplishes a number of objects, namely, the provision of means, effective during the maintenance of a connection, for eliminating variations or fluctuations of voltage occurring along the surface of the liquid insulating medium contained in the device; —the provision of novel and simplified operating means for breaking such a connection successively at a plurality of points, i. e., at a point within the liquid insulating medium and then at a point disposed within an air space; and the provision of simplified and improved means for effectively and reliably operating the mechanism from the outside. The structure of the set of switch mechanism shown in Figure 1 is described below.

Attached to the transversely extending mounting plate 34, (shown particularly clearly in Fig. 2) are two bearing members, one on either side and depending therefrom, as indicated by the reference numerals 66 and 67. At the lower end of these members and transversely connecting the same, is a square bar 68, being rotatably secured in the members 66 and 67 as indicated at 69 and 70. The members 66—67 and the bar 68 may be made of

suitable wood. Contacts such as 71, 72 and 73, one for each set of mechanism, are secured to the bar 68. It will be observed that a lever is integral with each contact and projects therefrom as is indicated in Fig. 1 at 74, and that this lever connects with a link system comprising the links such as 75 and 76 and the lower link portion 77 of the movable contact rod 65, which slides within an opening of the terminal link 64. The connection between the cable 24 and the line 60 is thus maintained through the connector extending through the insulator 39, contacts 55, 71—74, link 77, contact rod 65, link 64, terminal lug 61, line or cable 60.

Assuming now that the lever contact 71—74, which is mounted on the transverse bar 68, is moved in an anti-clockwise direction, it will be seen, that the connection is broken first between the contact 71 and the yieldable contact 55, and, if the anti-clockwise movement is continued, the contact 65 will be moved downwardly and will slide out of engagement with the link 64. The contacts 55 and 71 are immersed in a suitable liquid insulating medium such as oil, the oil level being indicated by the reference numeral 78. The terminal contact link 64 cooperating with the movable contact 65 is disposed above the oil level. Accordingly, if such anti-clockwise movement of the contact lever 71—74 occurs, the connection between the contact 55 and the terminal contact 64 will be broken, first by the disengagement of the contact 71, within the insulating oil, and then by the disengagement of the movable contact rod 65 from the terminal contact 64 within the air space above the oil level.

The link members 75 and 76 may be made of insulating material. It will be understood, of course, that the switch mechanism just described is individual to a set of connections. The transverse bar 68 is common to all sets and carries the lever contacts such as 71—74. The manner in which the anti-clockwise motion of the lever contacts 71—74 is effected is as follows:

An operating shaft 80, clearly shown in Figure 2, is mounted on the top portion 12 of the housing by means of a suitable bracket 81 and bushing 83, so that the shaft projects from the housing and may be operated by means of its square end 82. A packing gland may be inserted in the bushing 83, and a suitable sleeve nut 84 may be employed for completing the assembly. The shaft 80, extending into the top portion 12 of the housing, is adapted to actuate a toggle joint comprising the members 85 and 86. The latter connect with an angular lever 87 keyed to the shaft 88 extending transversely across the top portion 12 of the housing, as is particularly shown in Fig. 2. The shaft 88 may be mounted at its ends in suitable bearings or brackets such as 89.

When the shaft 80 is actuated by means of a crank or key or the like, turning in clockwise direction (as shown in Fig. 1), the toggle link 85 will move downwardly, thereby actuating the toggle link 86 and throwing the angular lever 87 in anti-clockwise direction, rocking the shaft 88. Keyed to this shaft are levers, such as 87'-99 which are linked with the downwardly extending links such as 76 at point 99' indicated in Figure 2 in the form of a short shaft. Accordingly, when the shaft 88 is rocked as above explained, the levers such as 87' will move the links such as 76 downwardly, thereby actuating the link systems for moving the contacts such as 71 out of engagement with the corresponding yieldable contacts such as 55, and thereby moving the contact rods 65 in a perpendicular motion parallel to the links 76, so as to break the connection between the contact rods 65 and the terminal links 64 within the air space above the oil level. The interruption of the connections is successive, first at contacts 55-71 within the insulating oil contained in the device and then at 65-64 within the air space above the oil level. Plugs for inserting oil into the container and drain plugs may be provided. I have not shown such plugs because they are well known and do not affect the invention.

It is believed that the foregoing description discloses the operating mechanism with sufficient clarity so that a correct understanding may be obtained. The means for eliminating the transmission of voltage fluctuations or variations which occur along the surface of the insulating oil during the maintenance of a connection, will be explained next.

Mounted on the movable contact rod 65 of each set of connections is an insulating sleeve 95, the mounting of this sleeve being accomplished by means of insulating members arranged like spokes radiating from the inside wall of the insulating sleeve 95 and attaching to the corresponding contact rod 65, as is indicated by the numerals 96, 97, 98 and 99. The insulating sleeves may be suitably dimensioned according to the effect which it is desired to achieve. They can be readily exchanged by pulling the contact rods 65 out of engagement with the terminal links 64 and by sliding the sleeves 95 from the contact rods 65, and if desired replacing the same in a like manner with insulating sleeves of different dimensions. The insulating sleeves 95 move with the contact rods 65 up or down upon the establishing of the connections or upon breaking the connections, respectively. During the operation of the device, that is, during the time the connections are maintained, the insulating sleeves 95 will be positioned similarly as is shown in Fig. 1. In other words, the insulating sleeves are interposed between the

surface of the insulating oil and the contact rods 65, while the connections are maintained. Accordingly, the contact rods such as 65 will transmit to the terminal links such as 64 and, therefore, to the lines or cables such as 60, the potential obtaining within the insulating oil irrespective of the potential fluctuations occurring along the surface thereof. It will be appreciated that the function of the insulating sleeve is extremely important in view of the fact that creeping voltages always occur along the surface of the insulating oil which alter the voltage on the lines or cables. The insulating sleeve when properly proportioned does not merely reduce the voltage fluctuations, but actually eliminates the same.

In Figs. 3 to 7, inclusive, I have shown several embodiments of contacts which may be used advantageously in connection with oil switches in general and likewise with switches of the character described in this specification.

The contact arrangement shown in Fig. 3 consists of a kidney shaped yieldable contact designated by the numeral 100 and a yieldable spring leaf contact 101. A movable contact 102 is mounted on a squared shaft 103 and is provided with a lever projection 104 maintaining engagement with the leaf spring contact 101. The contacts 100 and 101 are in engagement with connectors disposed in the insulators such as 105 and 106, respectively, extending into the liquid insulating medium. The movable contacts 102 and 104 may be operated by means of the link lever 107 actuating the member 108. When the lever 107, and with it the member 108, are operated downwardly, the contacts 102-104 will move in anti-clockwise direction until the connection is broken between the contact 104 and the yieldable contact 101. The contact 102 always maintains connection with the yieldably kidney shaped contact 100.

Figs. 4 and 5 show an embodiment which is in principle similar to the embodiment shown in Fig. 3. There is, however, a difference in the provision of a contact member 109 which is removably secured to the contact lever 104' by screw means such as 110. Repeated operation of this contact arrangement causes wear on the contact 104' and on the contact member 109, respectively, due to the arcing occurring between the contact 109 and the leaf spring contact such as 101'. The contact member 109 is removable and, therefore, it can be exchanged if damaged by arcing. Instead of providing a kidney shaped contact as shown in Fig. 3 there is provided a U-shaped contact 111. Arranged slidably within the depending legs of this contact is the contact 112 being integral with the contact lever 104' and mounted on a square shaft such as 103'. The structure is in other respects similar to

- the one described in connection with the embodiment shown in Fig. 3, except that I employ a push rod such as 113 pivotally mounted at 114 on the contact lever 104. 5 The contact members 101' and 111 are mounted in conductive engagement with corresponding connectors disposed within insulators 105'—106'.

The embodiment shown in Fig. 6 shows a 10 further development of the contact arrangement along the lines of the contact arrangement shown in Figs. 4 and 5. The difference of this arrangement with regard to the previously described embodiments resides in the 15 use of a U-shaped contact 115 in place of a yieldable contact such as 101 and 101' shown in the other embodiments. A contact 116 on a contact lever 117 operates within the legs of the U-shaped contact 115 in the same 20 manner as the contact 112' operates within the legs of the U-shaped contact 111'. The mounting of the movable contacts on a square carrier shaft and the operation of these contacts, is substantially the same as the one 25 described previously.

In Fig. 7 is shown a movable contact arrangement having a body 118 clamped around a rotatable carrier shaft 119. At the ends of the arms of this movable contact body are 30 mounted the contacts 120 and 121 by means of bolts 122 and 123, respectively. Either of these contacts 120 and 121 is removable from the arms of the contact body 118. The contact 121 engages the yieldable arcuate 35 contact spring 124 which is mounted in conductive engagement with a connector disposed within the insulator 125, and the yieldable spring leaf contact 126 is mounted in conductive engagement with a connector disposed within the insulator 127. The operation 40 of the contacts is achieved by means of rocking the shaft 119 and thereby moving the contact 121 over the yieldable arcuate contact 124 and operating the contact 120 out of engagement or into engagement with the 45 spring leaf contact 126.

It will be realized that the structure shown in Figures 1 and 2 includes many novel features which will be appreciated by those experienced in the art. The contacts shown in the Figures 3 to 7, inclusive, also disclose simplified and highly efficient contact arrangements presenting features of advantages with simplified structures. Changes 55 may be devised in details of the structure of the several elements and parts and in the form and manner in which they are assembled. It is therefore to be understood that I have shown specific structures in order to 60 show embodiments of my invention for the purpose of guiding others in realizing the same in practice, but not for indicating its structural or functional limitations. What I believe is new is pointed out in the appended claims. 65

I claim as my invention:

1. A combined oil and air break disconnect switch comprising a housing containing an insulating medium, a pair of conductors entering said housing, a pair of connector means disposed on the same level on opposite sides of said housing for receiving said conductors, terminal means connected to each of said connectors, one of said terminal means being disposed within said medium and the other being disposed above the level of said medium within said housing, a movable contact slidably disposed within the terminal above said level of said medium, a movable contact engaging said terminal within said medium, link means for simultaneously moving said contacts, and operating means projecting from said housing for actuating said link means to move said contacts successively out of engagement with said terminal means. 75 80 85

2. An oil and air break disconnect switch, comprising, in combination, a housing containing insulating oil, a pair of conductors entering said housing on the same level from 90 opposite sides thereof, a pair of connector means, one connected to each of said conductors within said housing, one of said connector means extending into said insulating oil and the other disposed above the level of 95 the same, removable contact means cooperating with each of said connector means for maintaining connection between said connectors, means for moving the contact means within said insulating oil out of engagement 100 with the connector therein, and lever means extending from said contact means for moving said contact means above said oil level out of engagement with the connector thereat. 105

3. In an oil switch, a first terminal immersed in insulating oil, a second terminal disposed above the level of said oil, a rotatable contact cooperating with said first terminal, a slideable contact cooperating with said second terminal, a lever integral with said first contact movably engaging said second contact for maintaining conductive relation therebetween, a toggle joint, link means connecting said toggle joint with said lever, and means projecting laterally from said switch for actuating said toggle joint to move said link for operating said lever to disengage said rotatable contact from said first terminal within said oil and to disengage said slideable contact from said second terminal above said oil level. 110 115 120

4. A switch of the class described, comprising, in combination, a container consisting of a lower housing portion for receiving a liquid insulating medium, an upper housing portion for inverted attachment to said lower portion, two apertures of substantially the same dimensions provided on opposite sides in said upper portion on the same level, 125 130

cover means for interchangeable attachment to said upper portion for closing said apertures, means in each cover for introducing a conductor into said upper portion of said switch, terminal means secured to each of said conductors within said switch and disposed coaxial therewith and radially spaced from each other, one of said terminals extending into and being immersed in said medium 10 and the other terminal disposed above the level thereof, a contact projecting through the level of said medium into the terminal above said level and being slideable therein, a rotatable contact cooperating with the terminal immersed in said medium, means for actuating said contacts to break an established connection by successively disengaging said rotatable contact and then said slideable contact from said terminals, and means on said 20 slideable contact for maintaining thereon the potential obtaining on said immersed contact regardless of potential variations along the level of said medium.

5. In an oil switch of the class described, a box containing insulating oil, a first stationary terminal contact immersed in said oil, a second stationary terminal contact disposed above the level of said oil, a rotatable contact cooperating with said first contact, a contact rod projecting through the level of said oil into said second stationary contact and slideably disposed therein, link means immersed in said oil for actuating said rotatable contact to disengage said first contact, means 35 on said rotatable contact and on said link means for actuating said contact rod to slide out of engagement with said second stationary contact, and removable insulating means carried by said slideable contact rod for transmitting to said second stationary terminal contact disposed above said oil level solely the potential obtaining on said immersed stationary contact terminal when the connection is maintained between said terminals.

45 6. In an oil switch of the class described having a terminal immersed in oil and a terminal disposed above the oil level, a movable contact cooperating with said immersed terminal, a movable contact cooperating with said other terminal, means for actuating said contacts to interrupt the connection between said terminals, and removable and exchangeable insulating means of predetermined properties associated with the movable contact cooperating with said other terminal for insulating said contact against the variable potential obtaining along said oil level during the maintenance of a connection between said terminals.

55 7. In an oil switch of the class described having a terminal immersed in oil and a terminal within an air space above the oil level, a contact rod slideably engaging said latter terminal and extending through the oil level into movable conductive engagement with

said first immersed terminal, the potential obtaining on said immersed terminal being transmitted to said air terminal by means of said contact rod, and a tubular insulating member removably secured to and spaced from said contact rod for eliminating the transmission of variable voltage fluctuations on the surface of said oil.

8. In an oil switch of the class described having a terminal immersed in oil and a terminal within an air space above the oil level, a contact rod slideably engaging said latter terminal and extending through the oil level into movable conductive engagement with said first immersed terminal, the potential obtaining on said immersed terminal being transmitted to said air terminal by means of said contact rod, a tubular insulating sleeve removably secured to and spaced from said contact rod immediately above and below the oil level for insulating said contact rod against variable creeping voltages on the surface of said oil while a connection is maintained between said terminals, link means for actuating said contact rod, and means operable from the outside for actuating said link means to move said contact rod for successively interrupting said connection first at said immersed terminal and then at said air terminal above said oil level.

9. In an oil switch of the class described having a terminal immersed in oil and a terminal within an air space above the oil level, a contact rod slideably engaging said latter terminal and extending through the oil level into movable conductive engagement with said first immersed terminal, the potential obtaining on said immersed terminal being transmitted to said air terminal by means of said contact rod, a tubular insulating sleeve removably secured to said contact rod and spaced therefrom at a point immediately above and below said oil level for insulating said contact rod against variable potential fluctuations along the surface of said oil while a connection is maintained between said terminals, link means for actuating said contact rod, toggle means for operating said link means, and means for actuating said toggle means from the outside to operate said link means for moving said contact rod to effect an interruption of said connection successively at said immersed terminal and then at said terminal within said air space above said oil level.

10. A switch device of the class described, comprising a container having a bottom portion and a top portion joined by flanges and forming a housing, certain of said flanges projecting laterally into said housing, mounting means supported by said projecting flanges within said housing, a plurality of insulators carried by said mounting means, connectors disposed within said insulators, conductors secured to said connectors within

5 said top portion and terminal contacts secured thereto within said lower portion of said housing, a common rotatable shaft transversely disposed within said bottom portion of said housing and carried by said mounting means, switch contacts movably supported by said shaft for establishing engagement with said terminal contacts of said connectors within said bottom portion, a rotatable common operating shaft extending transversely across said top portion of said housing, links secured to said shaft for actuating said switch contacts, contact rods movably cooperating with said switch contacts and projecting 10 from said bottom portion into said top portion of said housing, stationary terminals cooperating with said contact rods within said top portion of said housing and conductors connected to said stationary terminals, and toggle means for rocking said transverse shaft within said top portion to actuate said links for operating said switch contacts mounted on said rotatable transverse shaft within the bottom portion and to move 15 said rod contacts to interrupt the connections between said switch contacts and said terminal contacts within said bottom portion and between said contact rods and said stationary terminals within said top portion of said housing.

20

25

30

nection, and means interposed between said switching means and said surface of said medium for controlling said variations.

In witness whereof, I hereunto subscribe my name this 1st day of February, 1932. 70

11. In an oil switch of the class described, comprising a container partially filled with insulating oil, a connector in said container extending into said oil, a cable connected to 35 said connector, a second connector disposed within said container above the level of said oil, a line connected to said second connector, switching means within said container for establishing a connection from said cable to 40 said line, there being potential fluctuations along the surface of said oil level during the transmission of current over said established connection, and means associated with said switching means within said container for 45 preventing the transmission of said potential fluctuations to said line.

12. In a device of the class described, comprising a container partially filled with a liquid insulating medium, a connector in said container disposed so as to project therein from said medium to the upper portion of said container, a first conductor laterally entering the upper portion of said container and connected to said connector, a second connector laterally disposed within said upper portion of said container above the level of said medium, a second conductor connected to said second connector, said first and second conductors entering said device at substantially the same level, switching means within said container for establishing a connection between said conductors, there being potential variations along the surface of said medium in said container during the transmission of current over said established con-
